UNITED STATES PATENT OFFICE.

LOUIS BLÉRIOT, OF SURESNES, FRANCE.

COMPRESSED-FLUID DISTRIBUTER.

1,318,834.

Specification of Letters Patent.

Patented Oct. 14, 1919.

Application filed December 8, 1917. Serial No. 206,286.

To all whom it may concern:

Be it known that I, Louis BLÉRIOT, engineer, citizen of the French Republic, residing at Suresnes, Department of Seine, 5 France, have invented certain new and useful Improvements in Compressed-Fluid Distributers, of which the following is a specification.

The invention relates to compressed fluid 10 distributers; and it relates more particularly, among the apparatus of the kind in question, to those that can be utilized in the apparatus for starting explosion engines.

It has for its chief object to make the apparatus of the kind in question so that they 15 should work better than those hitherto designed.

It consists chiefly also—at the same time as in building the apparatus of the kind in 20 question so that they should have a longitudinally moving piston—in adding to the said piston such means that, when the said piston arrives at the end of its working stroke, the said means should occupy such a 25 position as to bring about simultaneously the shutting off of the admission of the compressed fluid to the operative face of the piston, and the opening of admission of the 30 said compressed fluid to its other face, so that the said piston returns to its initial position, the said means remaining then in the 35 position which they occupy, as long as the compressed fluid inlet conduit remains open.

Apart from this chief arrangement, it 40 comprises certain other arrangements, more explicitly referred to hereinafter.

It relates more particularly to certain methods of carrying out, as well as of applying, the said arrangements, and more particularly still, by way of new industrial products, to apparatus of the kind in question comprising application of the same arrangements, to special elements suitable for building them, as well as to explosion engines 45 which are started by means of such apparatus.

And it will be in any case clearly understood from the following description, as well as from the accompanying drawing which, 50 of course, is given merely by way of example.

The single figure of the said drawing shows, in axial longitudinal section, a compressed fluid distributor according to the

invention, applied to the starting of an explosion engine. 55

According to the invention, and more particularly according to that of the methods of carrying it out, as well as of applying it, to which refers more particularly the drawing, 60 when it is intended to build a compressed fluid distributor suitable for starting an explosion engine, the proceeding is as follows, or in a similar manner:

First of all, is made a cylinder body *a* 65 which is constituted for instance by means of a steel tube of circular cross-section.

An annular piston capable of moving in the interior of the cylinder *a* is built so that:

it should have a head *b* forming the piston proper and adapted to slide in the interior of the cylinder *a*, the said head being preferably constituted by leathers inclosed between a metal fitting constituted by two washers; 70

it should have a rod *b'* secured to the metal fitting, arranged concentrically with the cylinder *a*, the said rod *b'* being constituted by a metal tube of circular cross-section; 75

and so that it should have, secured to the end of the rod *b'* projecting from one of the cylinder ends when the piston is at the end of its return stroke toward the other end, a cap *b*² in the form of a cup, the said cup being 80 provided in the portion of its bottom situated around the rod *b'*, with openings *b*²⁰ and being so secured to the said rod *b'* that its edge should be in line with the cylinder *a*. 85

On the end of the cylinder, facing the cap *b*², is screwed a cover *a'* adapted to guide the rod *b'* of the piston; the said cover is provided with openings *a*¹⁰, and the rod *b'* is made of such length that when the cap *b*² is in contact with its edge with the cover *a'*, the piston *b* is at the bottom of its stroke toward the other end of the cylinder *a*. 95

This main piston structure has a supplemental piston *c* adapted to move in the interior of the rod *b'*, and the said piston *c* is 100 preferably constituted by means of two stamped out leathers inclosed in a metal fitting.

The piston *c* is secured to a rod *c'* concentric with the rod *b'*, the said rod *c'* being 105 constituted by a tube of circular cross-section of an outside diameter perceptibly smaller than the inside diameter of the rod *b'*.

The rod c' in advance of the front face of the piston c , has secured thereto a cup c^2 of an outside diameter slightly smaller than the inside diameter of the rod b' , and the 5 said rod c' is provided between the front face of the piston c and the cup c^2 , with openings c^{10} .

Into the interior of the tube b' , and beginning with its free end, is introduced the 10 structure just described, starting with the piston c , the latter occupying the position relatively to the bottom of the cap b^2 , as shown in the drawing; the leathers of the piston b having a widened portion b^0 surrounding the rod c' and forming a tight joint.

In the wall of the tube c' , and a little in front of the piston b , at the side opposite to its rod b' , is an opening c^{100} ; into the 20 interior of the tube c' is then introduced a tube d of an outside diameter perceptibly smaller than the inside diameter of the said tube c' ; one of the ends of the said tube d is connected to the opening c^{100} and its other end 25 is made to open at the face of the piston c opposite the bottom of the cap b^2 .

On the end of the cylinder a is screwed a 30 cover a^2 having a central cylindrical hole a^{20} with a seat adapted to receive a valve, and at a suitable point another hole a^{200} , is 35 formed and provided with a seat for another valve.

The tube c' , is threaded and therein is secured a tube e of a diameter smaller than the 40 diameter of the hole a^{20} , and has at its outer extremity a valve e' adapted to engage with the seat of the hole a^{20} , a spring e^{10} having been previously inserted between an inwardly projecting central terminal wall of the cover a^2 , and the valve e' . The free end 45 of the said tube e is caused to rest in a recess a^0 provided in an outwardly projecting central end wall of the cover a^2 , the said recess comprising a seat adapted to cover a part e^0 of the rod e forming a valve.

At the end of the rod c' and on the rod e is secured a rod f , to the end of which is fitted a rod f' secured to a valve f^2 adapted to engage with the seat of the hole a^{200} .

When the piston b is at the end of its return stroke, the valve e' is away from its seat, and the valve f^2 is held in contact with its seat.

Moreover, the rod c' is provided with a 55 stop g with which engages a finger g' mounted on a spring blade g^2 secured to the cover a^2 .

To the shaft i of the engine which is to be rotated or to an intermediate shaft communicating its movement to the engine shaft, 60 is secured a ratchet wheel j ; with the said ratchet wheel engages a pawl j' which is pivoted at a suitable point of the lateral face of a grooved pulley k mounted loose on the shaft i , or on a shaft arranged in line with

the said shaft i , and the pawl j' is connected by cable m passing over the groove of the pulley k to an attaching flange b^{200} secured to the bottom of the cap b^2 , the said flange b^{200} being preferably cast together with the 70 said cap b^2 .

In the same way, the pawl j' is connected to a cable n wound in the direction opposite to that of the cable m in the groove of the pulley k ; the cable n being caused to pass 75 over a guide pulley n' , then through the interior of a tube o , which is arranged parallel to the axis of the cylinder a , along the latter, the said tube being suitably guided along the cylinder a , and connected at one 80 of its ends to the flange b^{200} , and cable n being secured to the other end of the tube o .

The operation of the improved mechanism in starting an explosion engine therewith is as follows:—

The various parts being in the position shown, a compressed fluid, for instance air, is admitted through the conduit h and the hole a^{20} into the cylinder a , and exerts a pressure against the piston b and also passes through the opening c^{100} into the tube d , and also exerts a pressure on the central portion of the cap b^2 . Under these combined actions, the piston b will be moved in the cylinder a and will exercise a traction on the cable m , the air forced by the said piston escaping into the atmosphere through the openings a^{10} . The ratchet wheel j will be driven by the pawl j' , and the engine shaft i will be rotated until the said piston b arrives at the end of its stroke toward the left, 95 when the engine will be therefore started. The piston b will return to its initial position in the following manner:

A short time before reaching the end of its 100 working stroke, the piston b through its leathers b^0 , engages the edge of the cup c^2 , and produces a movement of the rod c' , and the stop g is released by the locking finger g' . The valve e' then engages with the seat of the hole a^{20} , the end of the rod e being disengaged from the recess a^0 ; the valve f^2 is moved simultaneously away from its seat, and the interior of the cylinder a is opened 110 to communication with the atmosphere through the hole a^{200} , and the air contained in the cylinder in advance of the piston b escapes outward, and the air contained between the piston c and the bottom of the cap b^2 gets into the cylinder a through the tube d in order also to escape outward through the hole a^{200} . During this time, the compressed air admitted through the conduit h , gets into the interior of the tube c' , through the tube e , escapes through the openings c^{10} and acts 115 on the central portion of the piston b , comprised between the tube b' and c' , the piston b returns gradually back until it reaches the end of the stroke, driving with it the tube o ; so that the pawl j' returns to the position 120

shown in full lines in the drawing, and the various parts remain in the position which they occupy owing to an equilibrium between the pressure of the air imprisoned between the tubes b' and c' , and of the air coming from the conduit h . In order to enable the apparatus to work again, it is necessary to move the valve e' away from its seat; it is sufficient for the purpose to close the conduit h , the equilibrium is then broken by the spring e^{10} , the rod c' is shifted, and the finger g' engages over the stop g , the valve e' is moved away from the seat, the valve e^0 is pressed against its seat, the valve f^2 closes the hole a^{200} , and to make the apparatus work again, it will be sufficient to open the conduit h .

It goes without saying that the invention is by no means limited to that of the methods 20 of carrying it out, of applying it, which has been particularly described; it comprises on the contrary any modifications.

Claims:

1. A compressed fluid distributor of the 25 class specified comprising a cylinder, a longitudinally movable piston therein having a tubular piston rod, a supplemental piston and tubular piston rod movably mounted in the first named piston and piston rod, a cap 30 connected to the one extremity of the first named piston rod, means for establishing communication between a point in advance of the first named piston through the supplemental piston to the said cap, means for supplying a compressed fluid to the first named 35 piston, said fluid passing through the supplemental piston to the cap, and means for shutting off the supply of compressed fluid when the first named piston has reached the 40 terminal of its stroke.

2. A compressed fluid distributor particularly adapted for starting explosion engines comprising a cylinder having a main piston and tubular stem, a cap on one end of the 45 main stem, a supplemental piston and tubular stem within the main piston and tubular stem, means for supplying a compressed fluid to the pistons and stems, and valve means automatically operated to control the 50 operation of the pistons and stems and pre-

vent the same from moving into position for a repetition of operation until the supply of compressed air has been cut off.

3. A compressed fluid distributor of the 55 class specified particularly adapted for starting explosion engines, comprising a cylinder and concentrically arranged pistons and tubular stems, means for supplying a compressed fluid to the pistons and stems, and means for controlling the supply of compressed fluid and operative to prevent a repetition of the operation of said pistons and stems until the supply of compressed air has been cut off.

4. A distributor of the class specified comprising a chamber, a main piston and tubular rod, a supplemental tubular rod on which the main piston rod has movement, the supplemental tubular rod having a spring actuated valve at one end and a supplemental 60 piston at the other, the supplemental rod being provided with means for admitting the operative medium thereinto, and means for supplying a compressed fluid to the cylinder and pistons and rods. 65

5. A distributor of the class specified, comprising a cylinder, a main piston and hollow rod movably mounted in the cylinder, means for supplying compressed fluid to the cylinder, and a supplemental hollow rod on which 70 the main hollow rod and pistons have movement, the said supplemental hollow rod having a spring actuated valve at one end to control the admission of the compressed fluid into the cylinder to act on the main piston, 75 the supplemental hollow rod also having a piston at its opposite end and a tube extending thereinto and through the same and the supplemental piston, the supplemental hollow rod also being provided with openings 80 therethrough adjacent to its piston and having a cup therein for engagement with the main piston. 85

In testimony whereof I have hereunto set my hand in presence of two subscribing witnesses. 90
